UNITED STATES PATENT OFFICE.

LOUIS N. VINCENT, OF PRESCOTT, ARIZONA.

DRAIN-VALVE.

1,091,463.

Specification of Letters Patent. Patented Mar. 24, 1914.

Application filed November 17, 1913. Serial No. 801,510.

To all whom it may concern:

Be it known that I, LOUIS N. VINCENT, residing at Prescott, in the county of Yavapai and State of Arizona, a citizen of the United States, have invented certain new and useful Improvements in Drain-Valves; and I do hereby declare the following to be a full, clear, and exact description of the invention, such as will enable others skilled in the art to which it pertains to make and use the same.

My invention relates to improvements in drain valves.

It has for its object to provide an automatic drain valve for steam pipes, steam cylinders and the like.

It further has for its object to provide a drain valve which is automatically closed by steam pressure and automatically opened when released from steam pressure.

It further has for its object to provide a drain valve which when employed, for instance, in connection with a steam cylinder will automatically drain the high pressure pipe connected with the steam chest and the low pressure pipe connected with the steam cylinder.

It further has for its object to provide a drain valve having a minimum number of parts or members and to mount the working elements thereof in one part so that when said part is removed the working elements will be removed.

It further has for its object to provide a drain valve which can be employed to simultaneously drain one or more pipes and cylinders.

It further has for its object to provide a drain valve which is simple, inexpensive and durable in construction and easy and effective in operation.

Referring to the drawings: Figure 1 is a central vertical section of the drain valve showing it in the position it occupies when under pressure closing both drain ports.

Fig. 2 a central vertical section of the drain valve showing it in the position it occupies when released from pressure opening both drain ports. Fig. 3 a top plan view of the drain valve. Fig. 4 a vertical section of the outer part or member of the drain valve.

Fig. 5 a vertical section of the inner part or member of the drain valve with the valve therein. Fig. 6 a vertical section of the

outer part of another form of the drain valve.

In the drawings in which like reference characters denote like parts throughout the several views, 1 represents the drain valve having an outer member or casing 2 and an inner member or plug 3. The outer member or casing 2 is provided with a chamber the lower part 4 of which is made larger in circumference than the upper part 5, thus forming a valve seat 6, a high pressure inlet 7 at the top which, if the valve is employed in connection with a steam cylinder, is connected with the steam chest by means of pipe 8, a high pressure by-pass 9 connecting the lower and upper parts 4 and 5 of the chamber, and a low pressure port 10 adapted to be connected with the steam cylinder by means of a pipe 11. The inner member or plug 3 is provided with a body portion 13 which fits and is secured in the chamber 4 by means of screwthreads 14 engaging screwthreads 15 on the outer member, the upper end of said body portion abutting against the seat 6 of the outer member and provided with a chamber 16 communicating with the chamber 5 and having a high pressure port 18 communicating with the by-pass high pressure port 9 of the outer member 2 and the lower end provided with a low pressure port 19 communicating with the low pressure port of the outer member, an octagon shaped flange 20 abutting against the lower end of the outer member or casing 2, providing means whereby a wrench or other tool may be applied to insert or remove the plug.

A valve 21 is located in the chamber 16 of the inner member or plug provided with a hollow stem 22, closed at its upper end, provided with outlet ports 23 and 24 and extending through a bore 25 in the inner member or plug having a screwthreaded boss 26 thereon. A spiral spring 27 is mounted on the upper end of the stem 22 within a recess 28 in the inner member or plug, the upper end of the spring bearing against the under face of the valve and the lower end against the bottom of the recess 28, said spring serving, when expanded, to hold the valve against the seat 6, establishing communication, by means of the by-pass high pressure port 9 and high pressure port 18 with the chamber 16, establishing com-

2

munication with the chamber 16 and the low pressure ports 10 and 19 and establishing communication with the chamber 16 and the hollow stem by means of the ports 23 and 24. By reason of the several ports being formed directly in the members, by boring, pipes are dispensed with and by reason of the plug member carrying the controlling valve and spring they will be readily moved or inserted with the plug without displacement and the valve seats can be readily ground.

In operation, steam under pressure passes through the pipe 8 from the steam chest into chamber 5 forcing the valve 21 upon the valve seat formed by the bottom of chamber 16 and compressing the spiral spring 27, closing the ports 18, 19, 23 and 24 and when the valve is released from steam pressure the spring 27 will expand forcing said valve against seat 6 opening ports 18, 19, 23 and 24 whereupon all the steam and water from steam chest and steam cylinder will pass through the high and low pressure ports 25 into the lower portion of the chamber 16, below the valve 21, and from thence through the ports 23 and 24 into hollow stem 22 and exhausts therefrom. When it is desired to drain a number of steam chests and steam cylinders the modified form of outer part of drain valve is used, as shown in Fig. 6, in which 29 indicates a series of high pressure ports and 30 a series of low pressure ports designed to be connected with a number of steam chests and steam cylinders respectively.

I do not wish to be understood as limiting myself to the specific details of construction and arrangement as herein described and illustrated, as it is manifest that variations and modifications may be made in the features of construction and arrangement in the adaptation of the device to the various conditions of use without departing from the spirit and scope of my invention and improvements. I therefore reserve the right to all such variations and modifications as properly fall within the scope of my invention and the terms of the following claims.

50. What I claim is:

1. In a drain valve, an outer member having a chamber provided with an inlet and an outlet, a by-pass high pressure port in said outer member, a low pressure port and means controlling communication between the high and low pressure ports and the outlet, substantially as described.

2. In a drain valve, an outer member having a chamber provided with an inlet, a by-pass high pressure port and a low pressure port in said outer member, an inner member having an outlet and means controlling communication between the high and low pressure ports and the outlet, substantially as described.

3. In a drain valve, an outer member having a chamber provided with an inlet, a by-pass high pressure port and a low pressure port in said outer member, an inner member provided with an outlet, a low pressure port communicating with the low pressure port of the outer member and means controlling communication between the high and low pressure ports and the outlet, substantially as described.

4. In a drain valve, an outer member having a chamber provided with an inlet, a by-pass high pressure port in said outer member communicating with said chamber, an inner member provided with an outlet, a low pressure port and means controlling communication between the high and low pressure ports and the outlet, substantially as described.

5. In a drain valve, an outer member having a chamber provided with an inlet, a by-pass high pressure port and a low pressure port in said outer member, an inner member having a chamber provided with a high pressure port communicating with the by-pass high pressure port of the outer member, an outlet and means controlling communication between the high and low pressure ports and the outlet, substantially as described.

6. In a drain valve, an outer member having a chamber provided with an inlet, a by-pass high pressure port in said outer member, an inner member provided with a chamber communicating with the first mentioned chamber, an outlet, a high pressure port communicating with the high pressure port of the outer member, a low pressure port and means controlling communication between the high and low pressure ports and the outlet, substantially as described.

7. In a drain valve, an outer member having a chamber provided with an inlet, a by-pass high pressure port and a low pressure port in said outer member, an inner member having a chamber communicating with the first mentioned chamber, an outlet, a high pressure port communicating with the by-pass high pressure port of the outer member, a low pressure port communicating with the low pressure port of the outer member and means controlling communication between the high and low pressure ports and the outlet, substantially as described.

8. In a drain valve having a member with a chamber provided with an inlet, a by-pass high pressure port and a low pressure port in said member, a valve having a hollow outlet stem with ports and controlling communication between the high and low pressure ports and the ports of the outlet stem, substantially as described.

9. In a drain valve, an outer member having a chamber provided with an inlet, a by-

pass high pressure port and a low pressure port in said outer member and an inner member provided with a valve having a hollow outlet stem with ports and controlling communication between the high and low pressure ports and the ports of the outlet stem, substantially described.

In testimony whereof, I have affixed my signature in the presence of two witnesses.

LOUIS N. VINCENT.
